MANIFOLDING BOOK

Harry Stevens, Oakland, Calif., assignor, by
mesne assignments, to Pacific Manifolding
Book Company, Inc., a corporation of Dela-
ware

Application April 1, 1932, Serial No. 602,457

27 Claims. (Cl. 282—24)

This invention relates to manifolding books, pads and the like, and is specially concerned with the kind in which each manifolding set in the book has one or more carbons which are individual to such set.

One of the most important objects of this invention is the provision of a manifolding sales-book having a number of manifolding units or manifolding sets, each unit including one or more carbon sheets individual to it and separate from the carbon sheets of other units so that in manipulating the book contact with the carbon is practically entirely avoided.

A further important object is the construction of such a book which will lend itself to the utilization of a large number of carbon sheets of relatively thin material having a relatively light coat of carbon and constructed so as to conserve and protect the carbon leaves at all times.

Other important objects of the invention are—the provision of a simple and practical book structure, or book element, which may be used to make up manifolding books or pads designed to furnish either two or three, or any practical number of copies at one writing; the provision of a simple, convenient and efficient means for facilitating the ultimate manual stripping or separation of the transfer leaves or carbons, from the record leaves; the provision of a practical arrangement wherewith a copy of the record may automatically be retained in the book though others of the records be torn out; the provision of a simple and efficient construction and arrangement of the leaves lending itself to covering the many carbon leaves employed and guarding against smudging by the carbon leaves; the provision of a practical and simple construction for holding the sheets of each manifolding unit, or manifolding set, in superposed registry and protecting the operator against contact with the carbons while inscribing and while operating the book; the provision of a practical and relatively inexpensive book in which the leaves may be of different qualities of paper or of different colors of paper, and the provision of a simple construction of book giving practically perfect copies, and a book which is adapted for very rapid operation.

Other objects of the invention will in part be obvious and will in part appear hereinafter.

The invention accordingly comprises the features of construction, combinations of elements, and arrangement of parts, which will be exemplified in the article hereinafter described and

the scope of the application of which will be indicated in the claims.

For a fuller understanding of the nature and objects of the invention, reference should be had to the following detailed description taken in connection with the accompanying drawings, in which:

Fig. 1 is a perspective view of a manifolding salesbook embodying the invention and adapted for the making of four copies at one writing, 10 namely, an original and three carbons;

Fig. 2 is a view showing two of the manifolding units or manifolding sets of Fig. 1 diagrammatically and with the leaves separated for clearer disclosure;

Figs. 3 to 12 inclusive are diagrammatic views similar to Fig. 2 but illustrating modified constructions of salesbooks embodying the invention;

Fig. 13 illustrates one of the carbon leaves, showing its clean end 15; and

Fig. 14 illustrates one of the carbon leaves having a notch permitting selective gripping.

In respect to all of the above figures, it is to be understood that similar reference numerals refer to similar parts throughout the several views.

Referring now more specifically to the drawings, and particularly to Figs. 1 and 2, a plurality of main manifolding units are associated in superposed relation to each other, the several units being bound together at the stub end of 30 the book, each manifolding unit comprising a plurality of leaves. In Fig. 1 one of the manifolding units is illustrated in detail with the leaves widely separated from each other for clearer disclosure. It is to be understood that the book 35 of Fig. 1 includes a plurality of these manifolding units in superposed relation to each other.

Referring more specifically to the construction of Fig. 1, each manifolding unit comprises a plurality of record leaves 1, 2 and 3, and two transfer sheets or carbon leaves 4 and 5, these five leaves being in superposed manifolding relation to each other and united together, as indicated at 6, outside the bound end of the book, and adapted for detachment as one from the book. 40 The leaves may be united together at their ends remote from the bound end of the book by any suitable and practical means. In the embodiment illustrated, these leaves of the unit are pasted together, the carbon sheets having clean 50 margins 15 for being pasted between the record leaves. Of course, the separate leaves might be stitched or stapled together at the ends 6. Viewed in some aspects of the invention, one or another of these leaves might be an integral fold of an 55

underlying leaf of the unit. In the book of Figs. 1 and 2, the top leaf and the bottom leaf of each unit are not only pasted to the other leaves at their ends 6 remote from the bound end of the book, but these top and bottom leaves are also bound in the book at the stub end thereof, the bound ends of these leaves being indicated at 7 and 8.

For ready detachment from the bound end of the book, each of the bound leaves is provided with a weakening line 9, these weakening lines in the different leaves being in superposed registry with each other.

Each of the carbon leaves 4 and 5 in each unit has its edge portion or free end 11 displaced from the adjacent edges 12 of the record leaves of the unit (which would be formed by detachment of the record leaves along the weakened lines 9) to provide a selective grip area in the unit, at which area the record leaves of the unit, when torn from the bound end of the book, may be gripped by the operator without gripping the carbon leaves. The point in each unit at which the selective grip area is provided is remote from the union of the carbons to the other leaves. Between the united ends 6 of the record leaves and the selective grip area just referred to, the record leaves have weakened transverse parting lines, indicated at 14, in superposed registry with each other. Although the intermediate carbon leaves 4 and 5 may also be weakened in superposed registry with the parting lines 14, it is preferred that they remain unweakened along such lines so that they are not so readily parted along such lines as are the record leaves.

In the embodiment illustrated in Figs. 1 and 2, the carbon leaf 4 is a single face carbon leaf, so as to transfer inscription to the bottom record leaf 3 of the unit without imprinting the back of the intermediate record leaf 2 immediately thereabove. Of course, a double face carbon leaf 4 may be utilized, if desired. The carbon leaf 5 is a double face carbon leaf so as to transfer the inscription to the top face of the underlying record leaf 2 of the unit and also to transfer the inscription to the under face of a supplemental record leaf 17, this supplemental leaf being bound in the book at the stub end and having its opposite end lying to one side of the union 6 of the other record leaves of the manifolding unit, so as ordinarily not to be grasped when the end 6 is grasped. In this wise, outer or free end of the supplemental leaf 17 need not be grasped when the pasted ends 6 of the other leaves are grasped for tearing the latter from the book along the weakening lines 9.

It is to be understood that for each main manifolding unit of the book of Figs. 1 and 2, there is a separate supplemental leaf 17, these supplemental leaves lying in interleaved relation in their respective units and being attached to the book so as to be retained therein after detachment of the main manifolding units from the book. As illustrated in Figs. 1 and 2, the supplemental leaves 17 are bound in the stub of the book along with the other bound leaves, and they lie between the bound and united record leaves in the respective units. In usual practice, the supplemental record leaves are of translucent material, as for instance tissue paper, so that the record made on the bottom face thereof by the carbon leaf 5 may be read in direct position by looking through the thickness of the supplemental leaf 17. Also, in usual practice, the supplemental leaves are to be retained in the

book after the main manifolding units have been detached, and in such circumstances the supplemental leaves need not have any transverse weakening lines along which they may be detached from the stub end of the book. However, weakening lines in the supplemental leaves for detaching purposes may be provided, if desired, as illustrated, for instance, at 19 (Figs. 1 and 2).

Also, in Figs. 1 and 2, the record leaves 1, 2 and 3 are usually of opaque paper, so that three direct reading records are obtained on durable, opaque paper, the fourth record being ordinarily on the bottom face of the translucent or tissue leaf 17. If desired, and to accommodate special conditions, the supplemental leaf 17 may also be made of opaque paper, in which case an additional carbon leaf might be included in each main manifolding set for transferring to the upper face of the opaque supplemental leaf. Or if the indirect reading on the bottom of the opaque supplemental leaf were satisfactory, said additional carbon leaf need not be employed.

Inasmuch as each manifolding unit has one or more of its own individual carbon leaves, inscription on one of the upper units has a tendency to be transferred to the underlying units. In order to avoid transferring to underlying units, a stop, or stop card or sheet, may be interposed between the unit being inscribed and the one lying therebetween. This stop card may be conveniently provided by a relatively thick manila sheet or card 20, which may be an integral extension of a backing or back 21 in which the several manifolding units composing the book are assembled and held or bound together, as for instance by the staples 22, which pass through a folded end of the backing and the stub ends of the bound leaves hereinbefore mentioned. It is to be understood, however, that any practical device for preventing transfer of inscription from one manifolding set to the other may be employed; as for instance, it may be desirable at times to have the bottom leaf 3 of each manifolding set made of a thickness and substance to serve as the stop.

The book of Figs. 1 and 2 may be operated as follows:

It will be understood that the record leaves of the book will usually have printed forms thereon and that these printed forms will be held in superposed registry because all the leaves are united together, as by the pasting at 6. Having interposed the stop card 20 between the manifolding unit to be inscribed and the next underlying unit, the inscription is made. Thereupon, the inscribed manifolding set is grasped at its free end 6, without grasping the adjacent end of the supplemental leaf 17, and the main manifolding set may then be readily torn from the book, the bound leaves readily parting along the weakening lines 9, closely adjacent the stub of the book. The separated or single manifolding set thus produced will have the carbons in position for causing any further inscription to be transferred to the underlying leaves of the separated unit. Thus, although the main manifolding unit has been parted from the book, it is still in condition for manifolding inscription, and the record leaves with printed forms are still held in superposed, accurate registry. For stripping, i. e., separating, the carbons from the record leaves of the inscribed manifolding unit, the united ends of the leaves are grasped by one hand of the operator at 6, and at the opposite end, or selective grip area, by the other hand, whereupon

by either a snapping action separating the ends, or a tearing action, the record strips will be parted along the lines 14, 15 and 16, and the carbon leaves will remain attached to the pasted union 6 and be drawn from between the record leaves with said detached pasted portion. Thus, in this manifolding book or pad, each manifolding unit is readily torn from the bound end of the book without tearing out the supplemental leaf 17, and thereafter the carbons of the torn-off set are readily removed as one from the record leaves by a simple operation.

In the book illustrated in Figs. 1 and 2, the manifolding units are bound to each other by staples 22. It is to be understood, however, that any suitable means may be employed for attaching the manifolding units together in the book, as for instance textile thread stitching of various sorts, pasting, impaling pins and the like, the object being firmly to secure the units together at the bound end of the book.

It is to be understood that the invention may be embodied in manifolding books designed for the making of either two or three copies at one inscription, or for the making of either five or six, etc. copies at one inscription. It is also to be understood that the invention may be embodied in manifolding books of different specific construction from the "quad" book illustrated in Figs. 1 and 2. For instance, a modified book is diagrammatically illustrated in Fig. 3. The construction of the book of Fig. 3 is exactly similar to the construction illustrated in Figs. 1 and 2, except that the intermediate record leaf 23 is not bound in the stub of the book, but its end 24 terminates in superposed registry with the weakening lines 9 in the record leaves 1 and 3.

Fig. 4 illustrates a book corresponding in construction with the book of Figs. 1 and 2, except that it is designed for the making of but three copies at one writing, and hence each manifolding unit includes only two record leaves 30 and 31 and only one carbon leaf 32 pasted together at their ends 6 remote from the bound end of the book, the carbon leaf 32 being double faced. In the book of Fig. 4 there is a supplemental leaf 17 in each unit corresponding to the similar unit in Figs. 1 and 2.

The book illustrated in Fig. 5 corresponds in all respects to the book illustrated in Fig. 4, except that the supplemental record leaf 17 is omitted, and hence but two copies are made at one writing, an original and a duplicate.

In the modified book diagrammatically illustrated in Fig. 6, the construction is similar to that in Fig. 5, except that the carbon 40 in each manifolding unit is bound into the stub of the book as indicated at 41, its opposite end being free from the union 6 between the original record leaf 42 and the duplicate record leaf 43.

Fig. 7 illustrates a still further modification over Figs. 5 and 6 in that the carbon leaf 50 is not only united to the original record leaf 51 and the duplicate record leaf 52 at their ends 6, as described in connection with the other figures, but the carbon leaf 50 is also bound into the stub of the book, as illustrated diagrammatically at 53. The carbon leaf 50 of this particular arrangement is preferably provided with a weakened line 54 in superposed registry with the weakened lines 9 in the record leaves, so that both the record leaves and the carbon leaf may readily be detached from the stub of the book as a unit. Inasmuch as the free ends of the detached, multi-ply manifolding unit of Fig. 7

are in substantial superposed registry with each other, the carbon leaf 50 may be provided with a cutout, notch or the like, as indicated at 55 (Fig. 14), so that the free ends of the record leaves 50 and 52 may be grasped at their corners, without grasping the carbon sheet 50, and the carbons stripped from between the record leaves 51 and 52 by tearing off the pasted margin 6 as hereinbefore explained, in connection with Figs. 1 and 2.

Fig. 8 diagrammatically illustrates a modified construction similar to Fig. 4, but in which the carbon sheet 60 is unattached and lies loosely between the record leaves 61 and 62, which latter are each bound in the stub of the book and also united at 6, as before explained. The carbon sheet 60 is double face to make inscription on the under face of the supplemental leaf 17 and the upper face of the duplicate record leaf 61. In the book of Fig. 8, inasmuch as the carbons are free, the carbon sheet may be coated fully therewith and the record leaves 61 and 62 need have no weakening lines adjacent the union 6 with each other, except for being separated from their union 6.

The book diagrammatically illustrated in Fig. 9 is generally constructed like the book of Figs. 1 and 2, but all the record leaves of each unit are not bound in the stub of the book. As illustrated in Fig. 9, the original record leaf 70, the duplicate record leaf 71, and the triplicate record leaf 72, are united to each other at their ends 6 remote from the stub of the book, carbons 73 and 74 being also interposed therebetween and united therewith, as explained in connection with Figs. 1 and 2. Also, in each unit a supplemental leaf 75 corresponding to supplemental leaf 17 of Figs. 1 and 2 is employed. But in Fig. 9 only one main record leaf 72 is secured in the stub end of the book. The record leaves 70 and 71 are enough longer than the carbon leaves 73 and 74 to provide the selective grip areas at the ends of the record leaves, as hereinbefore explained, the free ends of the record leaves 70 and 71 terminating in registry with the weakening line 9 along which the bound record leaves 72 may be detached from the stub of the book. Also the record leaves 70, 71 and 72, each has the weakened line 14 adjacent their union 6, the carbon leaves preferably being unprovided with weakening lines in registry with the lines 14. Both Figs. 1 and 2, and Fig. 9, illustrate "quad" books, the book of Fig. 9 being modified over Figs. 1 and 2 in the particulars noted.

The book of Fig. 10 is similar in construction to that of Fig. 9, except that as it is designed for making only three copies at one writing, the supplementary leaf 75 of Fig. 9 is omitted. Otherwise, the construction may be similar to that of Fig. 9 and include an original record leaf 80, a duplicate record leaf 81 and a triplicate record leaf 82 pasted at 6 to the clean ends of the carbon leaves 83 and 84, the carbon leaf 83 being a single face carbon as distinguished from the double face carbon 73 of Fig. 9. In the book of Fig. 10, the duplicate and original record leaves 80 and 81 are not bound in the stub, whereas the triplicate record leaf 82 is so bound and has a weakening line 9 for detachment from the stub.

In the modification illustrated in Fig. 11, the construction is similar to that of Fig. 10, only one leaf being bound in the stub, except that inasmuch as only a duplicate and an original are required in each manifolding unit, one of the 75

record leaves and one of the carbon leaves of Fig. 10 are omitted. Each manifolding unit in the book of Fig. 11 includes an original record leaf 90, a duplicate record leaf 91, and an intermediate, single face carbon leaf 92, having a clean end 93, united together at 6, as heretofore explained.

In the book of Fig. 12, which is designed for making triplicate copies, a supplemental record leaf 100, corresponding to leaf 17 of Figs. 1 and 2, is disposed in each manifolding unit between an original record leaf 101 and a duplicate record leaf 102, the original and duplicate being united to the intermediate carbon 103 at their ends 6, as before explained, the carbon leaf 103 being double face for transferring inscription both to the triplicate leaf 102 and the face of the supplemental leaf 100. The record leaf 102 is bound in the stub and has a weakened line 9 for detachment from the stub, whereas the record leaf 101 has a free end terminating in substantial registry with the weakened line 9 of the leaf 102. The supplemental leaf 100 is preferably to be retained in the book, but may be provided with a weakened line 104 for detachment from the book, if desired.

It is to be understood that the books illustrated diagrammatically in the figures of the drawings are each constructed along the line as described in connection with Figs. 1 and 2, except that the book and the manifolding units thereof are of modified construction as described in connection with the several diagrammatic figures. In respect to each modification, it is to be understood that when the several manifolding units or manifolding sets are assembled in superposed relation, they will preferably be enclosed in a backing similar to that described in connection with Figs. 1 and 2, and each will 40 also be equipped with a stop card as hereinbefore explained. In connection with any of the modifications, it is to be understood that the different units may be bound in the book by staples, textile threads, pasting or the like, and that the several leaves may be united together outside the bound end of the book in any suitable manner, as by textile stitching, or pasting, pasting being preferred and illustrated herein.

In the preferred construction, and especially when each manifolding unit includes three or more leaves, the pasting of the leaves together outside the bound end of the book as indicated at 6 provides each manifolding unit with a relatively stiff end margin which may be used as a handle in manipulating the unit. In each of the record leaves the weakening lines 14 separate the stiff margin or handle from the body of the leaf, thus providing for the removal of this relatively stiff handle from the manifolding unit when desired.

Since certain changes may be made in the above article and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. A manifolding book having, in combination, a binding, a plurality of manifolding units, each unit comprising a plurality of record leaves and a carbon leaf in superposed manifolding relation to each other, and united together outside of said binding for detachment as one from the book, one of the leaves in each unit having a binding ex-

tension projecting past the edges of certain other leaves and being bound in the book by said binding, the carbon leaf in each said unit having an edge portion displaced from the adjacent edges of the record leaves of the unit at a point remote from its union to the other leaves to provide a selective grip area in the unit, the record leaves, in each unit, having weakened, parting lines between their connection with said carbon leaf and said selective grip area. 5

2. A manifolding book having, in combination, a binding, a plurality of manifolding units, each unit comprising a plurality of record leaves and a carbon leaf in superposed manifolding relation to each other, and having union with each other outside the binding so as to remain attached together after detachment from the book, one of the leaves in each unit having a binding extension projecting past the edges of certain other leaves and being bound in the book binding, the carbon leaf in each said unit having an edge portion displaced from the adjacent edges of the record leaves of the unit at a point remote from its union to the other leaves to provide a selective grip area in the unit, the record leaves, in each unit, having weakened parting lines between their connection with said carbon leaf and said selective grip area, and supplemental record leaves bound at one end portion thereof in the book, one for each said unit, and each having its opposite 25 end free and lying to one side of the union of the other record leaves of its respective unit.

3. A manifolding book having, in combination, a binding, a plurality of manifolding units, each unit comprising a plurality of record leaves and a carbon leaf in superposed manifolding relation to each other, and having union with each other outside the binding so as to remain attached together after detachment from the book, one of the leaves in each unit having a binding extension projecting past the edges of certain other leaves and being bound in the book binding, the carbon leaf in each said unit having an edge portion displaced from the adjacent edges of the record leaves of the unit at a point remote from its union to the other leaves to provide a selective grip area in the unit, the record leaves, in each unit, having weakened parting lines between their connection with said carbon leaf and said selective grip area, and supplemental record leaves bound at one end portion thereof in the book, one for each unit, and each having a weakening line for detachment from the book and having its opposite end free and lying to one side of the union of the other record leaves of the unit. 40

4. A manifolding book having, in combination, a plurality of manifolding units, each unit comprising a plurality of record leaves and a carbon leaf in superposed manifolding relation to each other and united together for detachment as one from the book, said carbon leaf being carbonized on its opposite faces, one of the leaves in each unit having a binding extension projecting past the edges of certain other leaves and being bound in the book, and supplemental, translucent record leaves, one of which is in manifolding relation in each of said units and bound in the same binding with said binding extension. 60

5. A manifolding book having, in combination, a plurality of manifolding units, each unit comprising a plurality of record leaves and a carbon leaf in superposed manifolding relation to each other, and united together for detachment as one from the book, one of the leaves in each unit having a binding extension projecting past the edges 70

of certain other leaves and being bound in the book, and supplemental, translucent record leaves, one of which is in manifolding relation in each of said units and bound in the same binding with said binding extension, each of said units including a carbon leaf disposed to transfer inscription to the under face of said supplemental leaf.

6. A manifolding book having, in combination, a binding, a plurality of manifolding units bound in said binding, each unit comprising a plurality of record leaves and a plurality of carbon leaves in superposed manifolding relation to each other and all united together outside the book binding, one of said carbon leaves in each unit being double face, and supplemental translucent record leaves bound in the book binding, one for each of said units, said supplemental translucent leaves being in interleaved relation in their respective units and being attached in the book binding and in transfer relation with said double face carbon leaf.

7. A manifolding book having, in combination, a binding, a plurality of main manifolding units, each main unit comprising a plurality of record leaves and a carbon leaf in superposed relation to each other, supplemental leaves, one for each main unit, attached so as to be retained in the book after detachment of the main units from the book, a plurality of the leaves in the respective main units having binding extensions projecting past the edges of certain of the leaves and being bound in the book, said plurality of leaves being also united together outside the bound end of the book for detachment as one from the book.

8. A manifolding set having, in combination, two or more main record leaves in superposed relation to each other and united together at each of opposite ends, one or more carbon leaves in interleaved relation with said main record leaves and united therewith at one of said ends, a supplemental record leaf intermediate said main record leaves and united thereto at one end and free at the other end and terminating at its free end short of the union of the other leaves, one or more of said carbon leaves having a free end portion terminating short of the ends of the adjacent record leaves.

9. A manifolding set having, in combination, two or more main record leaves in superposed relation to each other and having attachment with each other adjacent to each of the opposite ends, a supplemental record leaf intermediate said main record leaves and united thereto at one end and free at the other end and terminating short of the other leaves at the latter end, weakened severance lines in certain of said leaves adjacent to and inside of each said attachment and transfer material interposed between said leaves in transfer relation therewith.

10. A manifolding set having, in combination, two or more main record leaves in superposed relation to each other and having attachment with each other at each of opposite ends, a supplemental record leaf intermediate said main record leaves and united thereto at one end and free at the other end, and transfer material interposed between said leaves, said main record leaves having weakened parting lines adjacent each of said opposite ends, the free end of said supplemental leaf terminating short of said attachment at the adjacent end of the set.

11. A manifolding book comprising a pack of manifolding sets, each set comprising top, bottom and intermediate record leaves, and intermediate transfer leaves bound together substantially at

marginal portions thereof, one intermediate record leaf of each set having a tear line adjacent the bound edge inwardly thereof and having a binding stub extending past the edges of the other leaves, the binding stubs of said intermediate leaves being attached together and to the book.

12. A manifolding book comprising a backing member and a pack of manifolding sets mounted on the backing member, each set including top, bottom and intermediate record leaves and intermediate transfer leaves bound together substantially at marginal portions thereof, each of the record leaves so bound having a weakened tear line adjacent its bound portion inwardly thereof, the carbon leaves being unweakened and having edge portions opposite the bound edge terminating short of the adjacent edges of the record sheets, one of the intermediate record leaves of each set which is bound to other leaves thereof having a binding stub remote from said bound portion and projecting past the edges of the other leaves bound together, the projecting edges of said intermediate leaves being attached together and to the backing member.

13. A manifolding book comprising a backing member, a pack of manifolding sets mounted on the backing member, each set comprising record leaves and interposed transfer leaves, edge portions of the leaves of each set having binding attachment with each other substantially at an edge portion of the pack, edges of the record and transfer leaves of each set being offset at the opposite edge portion of the pack, certain of the leaves of each set having readily breakable connection with the binding attachment to provide for separation of the record and transfer leaves, one intermediate leaf of each set having its edge portion opposite said binding attachment attached to the backing member and being weakened adjacent to one attached edge portion thereof to provide for detachment of the set from the backing member, leaves attached at an edge portion thereof to the backing member and positioned for interleaving respectively with the leaves of the sets having the binding attachment with each other, and a stop sheet adapted to be interposed beneath the top manifolding set of the pack.

14. A manifolding book comprising a backing member, a pack of manifolding sets mounted on the backing member, each set comprising record leaves and interposed transfer leaves, one of the transfer leaves of each set having a coating of transfer material on both sides thereof and the other of the transfer leaves having a coating of transfer material on the under side only, the transfer leaves of each set having binding attachment with each other and with the top, bottom and intermediate record leaves at one edge portion of the pack, an intermediate record leaf of each set having a detachable binding stub at the edge opposite said binding attachment, a thin paper record leaf lying upon the top of the double coated transfer leaf of each set, the thin paper leaves terminating at one end short of the binding attachments of the manifolding sets and having opposite edge portions lying between the said projecting detachable stubs of said intermediate record leaves, said detachable stubs and thin paper leaves being attached together and to the backing member, and a stop sheet adapted to be interposed beneath the top manifolding set of the pack.

15. A manifolding book comprising a backing

member and a pack of manifolding sets mounted on the backing member, each set comprising top, bottom and intermediate record leaves, and intermediate transfer leaves bound together at one edge portion thereof, one intermediate record leaf of each set having a tear line adjacent the bound edge inwardly thereof and its opposite edge extending past the edges of some of the other leaves, the projecting edge portions of said intermediate leaves being attached together and to the backing member.

16. A manifolding book comprising a backing member, and a pack of manifolding sets mounted on the backing member, each manifolding set including top and bottom record leaves and intermediate record and transfer leaves bound together at one edge portion thereof, the record leaves so bound having weakening lines adjacent their said bound edge portions whereby detachable stubs are provided, one of said record leaves only of each set being bound at its opposite edge portion to the backing member, and the other leaves bound in each stub being unattached to the backing member, whereby a pull exerted on a bound edge portion will detach from the backing member a set of leaves secured together and disposed in manifolding relation.

17. A manifolding book including, in combination, a backing member, a pack of manifolding sets mounted on the backing member, each said manifolding set including three record and two transfer leaves interleaved in transfer relation with each other, one of the transfer leaves of each set being two-faced or having a coating of transfer material on each side thereof and another transfer leaf having transfer material on one side only, the transfer leaves of each set having binding attachment with each other and with the record leaves, an intermediate record leaf of each set having a detachable stub projecting beyond one or more of the other bound leaves opposite to said binding attachment, a plurality of translucent record leaves one of which lies upon the top of the two-faced transfer leaf of each set, said translucent leaves terminating at one end short of the binding attachment of the manifolding sets and having binding extensions at their opposite ends lying between said detachable stubs of the intermediate record leaves, said detachable stubs and binding extensions being attached together and to the backing member.

18. A manifolding book including, in combination, a backing member, a pack of manifolding sets mounted on said backing member, each said manifolding set including top, bottom and intermediate record leaves and intermediate transfer leaves all having binding attachment with each other, each of the record leaves thus bound having a weakened tear line adjacent to said binding attachment, the transfer leaves being correspondingly unweakened and having edge portions opposite said binding attachment terminating short of the edges of the record leaves, one of the intermediate record leaves of each set having a binding extension at the edge portion thereof opposite to said binding attachment, said binding extensions being bound together and to the backing member.

19. A manifolding book including, in combination, a pack of manifolding sets, each said manifolding set including interleaved record and transfer leaves having binding attachment with each other, the edges of the record and transfer leaves of each set being off-set with reference to each other at points spaced from said binding

attachment, and certain of the leaves having readily severable connection with said binding attachment to provide for separation of the record and transfer leaves, one leaf of each manifolding set having a binding extension bound in the book, each of said last mentioned leaves being weakened adjacent to one attached part thereof to provide for detachment of its set from the book, and additional translucent record leaves carried by the book and positioned for interleaving respectively with the leaves of the sets.

20. A manifolding book including, in combination, a pack of manifolding sets, each said manifolding set including record and transfer leaves interleaved in transfer relation with each other, said record and transfer leaves of each set having binding attachment with each other, the edges of the record and transfer leaves of each set being relatively off-set at points thereof remote from said binding attachment, one leaf of each set having a binding extension bound in the book, and an additional leaf in each set bound to the backing member by said last mentioned binding attachment and having an opposite free end portion.

21. A manifolding book including, in combination, a pack of manifolding sets, each said manifolding set including record and transfer leaves interleaved in transfer relation with each other, said record and transfer leaves having binding attachment with each other, one record leaf of each set having readily detachable attachment to its set at the edge portion thereof disposed close to said binding attachment, and having a binding extension extending beyond some of the adjacent leaf edges, said binding extensions having binding attachment in the book.

22. A manifolding book including, in combination, a pack of manifolding sets, each said manifolding set including record and transfer leaves interleaved in transfer relation with each other, said record and transfer leaves having binding attachment with each other, one record leaf of each set having readily detachable attachment to its set at the edge portion thereof disposed close to said binding attachment and having a binding extension extending past some of the other leaves, said binding extensions having binding attachment with each other and in the book, and a weakened tear line on said last mentioned record leaf positioned adjacent to but inwardly of said last mentioned binding attachment.

23. A manifold book unit comprising an original sheet and a copy sheet of the same size in superposed relation, a carbon sheet between the same, said original and copy sheets having each a superposed alined transverse weakening line spaced a distance from one of their edges, said carbon sheet between the other said sheets having its one edge alined with the alined edges of the other sheets remote from said weakening lines, said carbon sheet extending between said other sheets to within a short distance of said weakening lines, means for securing all of said sheets together at a portion of one of their edges and means for securing only the original and the copy sheets together along the opposite edges.

24. A manifold book unit comprising an original sheet and a copy sheet of the same size in superposed relation, means for securing said sheets together at one of their edges, superposed alined transverse weakening lines in said sheets spaced a distance from said secured edges, a

carbon sheet between said sheets, said carbon sheet being of the same width as and shorter than the other two sheets and terminating a distance from said weakening lines, and attaching means attaching all of the said sheets together in permanent relation, said attaching means being located adjacent the edges of all the sheets opposite to the secured edges of the original and the copy sheets.

25. A manifolding book comprising record sheets and carbon sheets in superposed relation, means for securing all of the record sheets together at one edge thereof, a single superposed aligned transverse weakening line in each of said record sheets spaced a distance from the secured edges of said sheets, the said carbon sheets being shorter than the record sheets and terminating a distance from said weakening lines in the record sheets and attaching means for securing selected numbers of the record sheets and the carbon sheets together in permanent relation, said attaching means being located adjacent the edges of all the sheets opposite the secured edges of the record sheets.

26. A manifolding assembly including, in

combination, a plurality of relatively superposed record leaves, leaf attaching stubs positioned at remote marginal portions of the assembly in which a plurality of the record leaves are supported at both remote marginal portions thereof, transverse severance lines being positioned respectively between the stubs and leaves, and a transfer sheet bound at one edge portion in one of said attaching stubs.

27. A manifolding assembly including, in combination, a plurality of relatively superposed record leaves, leaf attaching stubs positioned at remote marginal portions of the assembly in which a plurality of the record leaves are supported at both remote marginal portions thereof, transverse severance lines being positioned respectively between the stubs and leaves, and transfer sheet bound at one edge portion in one of said attaching stubs, and having an opposite free edge terminating short of the opposite or remote weakened severance line and being unweakened adjacent to its attaching stub at points corresponding to the adjacent weakened lines of the record leaves.

HARRY STEVENS. 25
